UNITED STATES PATENT OFFICE.

GEORGE H. ZOUCK, OF ORANGE, NEW JERSEY, AND GEORGE L. WALKER, OF NEW YORK, N. Y., ASSIGNEES TO AIR REDUCTION COMPANY, INC., A CORPORATION OF NEW YORK.

BLOWPIPE.

1,376,991.

Specification of Letters Patent.

Patented May 3, 1921.

Application filed April 18, 1919. Serial No. 291,105.

To all whom it may concern:

Be it known that we, GEORGE H. ZOUCK and GEORGE L. WALKER, both citizens of the United States, and residing at Orange, Es-
5 sex county, New Jersey, and New York city, county and State of New York, respectively, have invented certain new and useful Im-
10 provements in Blowpipes; and we do hereby declare the following to be a full, clear, and exact description of the invention, such as will enable others skilled in the art to which it appertains to make and use the same.

This invention relates to blowpipes employing mixtures of combustible and oxidiz-
15 ing gases to produce high temperature flames for heating, welding and cutting operations.

Among the objects of the invention are increased efficiency in mixing the gases and
20 prevention of "flashback" or flame propagation rearwardly in the discharge passage of the tip.

A further object of the invention is the preservation of the controlling grooves or
25 depressions whereby the proportioning of the mixture is regulated in blowpipes of the character illustrated in the patents to George H. Zouck issued July 15, 1919, No. 1,310,100 and No. 1,310,101.

30 Further objects and advantages of our invention will be apparent as it is better understood by reference to the following specification when read in connection with the accompanying drawing in which;

35 Figure 1 is a longitudinal section through a blowpipe head and tip embodying our invention;

Fig. 2 is a section on the line 2—2 of Fig. 1;

40 Fig. 3 is a rear end view of the tip;

Fig. 4 is a section similar to Fig. 1 illustrating a slightly different form of our invention; and

45 Fig. 5 is a rear end elevation of the tip shown in Fig. 4.

One of the problems presented in blow-
pipe construction is to provide efficient mix-
ing of the combustible and oxidizing gases.
Another is to overcome the tendency of the
50 mixture to "flashback" and burn within the
tip or head of the blowpipe.

We have discovered that the difficulties experienced in securing proper mixing and

overcoming "flashback" may be success-
fully met by causing the primary mixture to 55 pass through a relatively restricted passage into an enlarged discharge passage which is preferably of uniform diameter throughout its length. The expansion of the gases into this discharge passage after passing the 60 more restricted passage results in a thorough admixture of the gases. Furthermore the relatively high velocity of the gases issuing from the restricted passage prevents flame propagation through the mixture and con- 65sequently overcomes the tendency to "flash-
back".

Blowpipe tips are generally constructed of copper or an alloy in which copper predominates and are, therefore, relatively soft. 70 In blowpipes employing grooves or depre-
sions in the rear end of the tip to convey one of the gases to the other for the purpose of producing the combustible mixture, such grooves may be reduced in cross sectional 75 area or otherwise distorted by the applica-
tion of pressure while the tip is in a highly heated condition. This difficulty may be readily overcome by the provision of an inset of metal, having a higher resistance to 80 deformation than copper, in which the grooves are formed and our invention con-
templates the employment of such an inset. Obviously, however, the restricted passage through which the mixture passes to the 85 discharge passage may be formed in an integral tip structure so that the advantages derived from the use of the restricted pas-
sage are not limited to a construction in-
volving the use of such an inset. 90

Referring to Figs. 1 and 3 of the draw-
ing, 5 indicates the head of a blowpipe having passages 6 and 7 for oxidizing and combustible gases supplied thereto through pipes 8 and 9. The passage 6 terminates in 95 a conical seat 10 and the passage 7 terminates in a channel 11 in the seat 10 sur-
rounding the end of the passage 6. A tip 12 having a discharge passage 13 is secured to the head 5 by a nut 14. At its rearward end the tip 12 is provided with an inset 15 which is preferably threadedly connected to the tip as indicated at 16 although it may be otherwise secured to the tip. The inset 15 is formed of a metal having a higher 100 105 resistance to deformation than the metal of

the tip which is usually copper or a metal in which copper predominates such as bronze. Various metals and alloys such as nickel, steel, etc., may be successfully employed and we do not desire to limit our invention to the use of any specific metal.

A passage 17 is formed in the inset 15 alining with the discharge passage 13 and of somewhat smaller cross sectional area 10 requiring the mixture to pass therethrough at a higher velocity and permitting expansion of the mixture upon entering the discharge passage. The inset 15 is provided with a conical recess conforming to the seat 15 and forming therewith a gas tight joint surrounding the ends of the discharge passages in the head. Preferably a channel 18 is formed in the face of the recess to register with the channel 11 when the tip is assembled with the head. The channel 18 is connected to the passage 17 by one or more grooves or depressions 19 through which the combustible gas is conveyed to and mixed with the oxidizing gas as the latter 25 issues from the passage 6 in the head.

The grooves or depressions 19 being formed in the metal, having relatively high resistance to deformation, are not readily reduced in cross sectional area by the careless application of pressure when in a highly heated condition and the blowpipe cannot, therefore, be readily injured by abusive treatment to which it is sometimes subjected by careless workmen. The restricted passage leading to the mixing and discharge passage insures proper mixture of the constituent gases and by requiring a high velocity at the entrance to the discharge passage, prevents flame propagation rearwardly through the restricted passage.

In Figs. 4 and 5, we have illustrated a slightly different form of our invention involving the same principles but in which 45 the inset 20' is limited to that portion only of the tip in which the restricted passage 20 leading to the discharge passage and the grooves or depressions 21 are formed. As will be readily understood the construction 50 illustrated in Figs. 4 and 5 presents the same advantages as have been hereinbefore enumerated.

Obviously various changes may be made in the form, arrangement and construction 55 of the blowpipe without departing from the invention. For example, the inset may be of the same metal as the body of the tip and may be employed to facilitate the manufacture of a blowpipe having a restricted 60 inlet to the discharge passage to improve mixing and prevent "flashback." The inset may, moreover, constitute a larger portion of the tip and where only the protection of the grooves or depressions is desired the 65 passage in the inset through which the mix-

ture enters the discharge passage of the tip may be of the same or greater cross sectional area than the tip.

We claim:

1. In a blowpipe, the combination with a head having passages for oxidizing and combustible gases, of a tip having a discharge passage, and an inlet of smaller cross sectional area to said discharge passage, said head and tip having coöperating conical sealing surfaces, and a groove in one of said surfaces and terminating at the mouth of said inlet whereby gas is conveyed from one of the passages in said head and mixed with the gas from the other passage in said head at the mouth of said inlet. 70 75 80

2. In a blowpipe, the combination with a head having passages for oxidizing and combustible gases and a projecting conical seat, of a tip having a discharge passage, an inlet of smaller cross sectional area to said discharge passage, a conical recess conforming to said seat and forming therewith a gas tight joint, and a groove in the recessed surface and terminating at the mouth of said inlet whereby gas from one of the 85 90 95 passages in said head is conveyed to and mixed with the gas issuing from the other passage at the mouth of said inlet.

3. In a blowpipe, the combination with a head having passages for oxidizing and combustible gases, a projecting conical seat and a channel in said seat communicating with one of said passages and surrounding the other, of a tip having a discharge passage, an inlet of smaller cross sectional area to said discharge passage, a conical recess conforming to said seat and forming therewith a gas tight joint and a groove in the recessed surface connecting said channel to said inlet when said tip is held in assembled relation with said head. 100 105 110

4. In a blowpipe, the combination with a head having passages for oxidizing and combustible gases and a seat, of a tip having a discharge passage and an inset of a metal having higher resistance to deformation than the body of said tip, said inset having a surface coöperating with said seat and a groove in said surface whereby gas is conveyed from one of the passages in said head and mixed with gas issuing from the other passage in said head at the inlet to said discharge passage. 115 120

5. In a blowpipe, the combination with a head having passages for oxidizing and combustible gases and a seat, of a tip having a discharge passage and an inset of metal having a higher resistance to deformation than the body of said tip, said inset having a surface coöperating with said seat to form a gas tight joint surrounding the ends of the passages in said head and a groove in said surface whereby gas from 125 130

one of the passages in said head is conveyed to and mixed with gas from another passage in said head at the inlet to said discharge passage.

- 5 6. In a blowpipe, the combination with a head having passages for oxidizing and combustible gases and a projecting conical seat, of a tip having a discharge passage, and an inset of a metal having a higher resistance to deformation than the body of 25
10 said tip, said inset having a conical surface coöperating with said seat and a groove in said surface whereby gas is conveyed from one of the passages in said head and mixed 30
15 with gas issuing from another passage in said head at the inlet to said discharge passage.
7. In a blowpipe, the combination with a head having passages for oxidizing and 20
20 combustible gases and a projecting conical seat, of a tip having a discharge passage and an inset of metal having a higher resistance to deformation than the body of said tip, said inset having a recessed surface

coöperating with said seat to form a gas 25
tight joint surrounding the ends of the passages in said head and a groove in said surface whereby gas is conveyed from one of the passages in said head and mixed with gas issuing from another passage in said 30
head at the inlet to said discharge passage.

8. In a blowpipe, the combination with a head having passages for oxidizing and combustible gases, and a seat, of a tip having a discharge passage, an inset in said tip 35
of metal having a higher resistance to deformation than the body of said tip, said inset being provided with an inlet of smaller cross sectional area to said discharge passage and a surface coöperating with said 40
seat and having a groove whereby gas is conveyed from one of the passages in said head and mixed with gas issuing from the other passage at the mouth of said inlet.

In testimony whereof we affix our signatures.

GEORGE H. ZOUCK.

GEORGE L. WALKER.
